UNITED STATES PATENT OFFICE

117,850

DESIGN FOR A HEATER

Bertrand B. Kahn and James L. Tupper, Cincinnati, Ohio, assignors to The Estate Stove Company, Hamilton, Ohio, a corporation of Ohio

Application August 17, 1938, Serial No. 79,402

Term of patent 7 years

To all whom it may concern:

Be it known that we, Bertrand B. Kahn and James L. Tupper, citizens of the United States of America and residents of Cincinnati, in the county of Hamilton and State of Ohio, have invented a new, original, and ornamental Design for a Heater, of which the following is a specification, reference being had to the accompanying drawing, forming a part thereof and in which the single figure is a perspective view of a heater embodying our new design. The side of the heater not shown is substantially similar to the side which is shown in the drawing.

We claim:

The ornamental design for a heater, substantially as shown and described.

BERTRAND B. KAHN.

JAMES L. TUPPER.
